UNITED STATES PATENT OFFICE.

GUY A. TOMLINSON, OF DETROIT, MICHIGAN.

DESIGN FOR A RING SETTING.

Application filed November 12, 1927. Serial No 24,093. Term of patent 3½ years.

To all whom it may concern:

Be it known that I, GUY A. TOMLINSON, a citizen of the United States, residing in the city of Detroit, county of Wayne, Michigan, have invented a new, original, and ornamental Design for a Ring Setting, of which the following is a specification, reference being had to the accompanying drawings forming part thereof.

Figure 1 is a top plan of the ring setting.

Figure 2 is a side elevation of the same.

Figure 3 is a cross section taken in the plane of line 3—3, Figure 1.

I claim:

The ornamental design for a ring setting substantially as shown and described.

GUY A. TOMLINSON.
